UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,964, dated July 1, 1890.

Application filed April 15, 1890. Serial No. 348,112. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

10 The drawing shows an umbrella or cane handle illustrating my new design.

A is the upwardly-extending portion of the body, and terminates in the crook B, having its point E made rounded and plain. At intervals in the body and crook there are enlarged portions D, between which the surface is depressed and formed with slightly spiral or twisted grooves or ribs.

F represents the grooves, and the raised portions between them would form ribs. 20

The body part A is finished at the bottom by a base-band C, rounded and highly ornamented.

The handle is made of any suitable material. 25

Having now described my new design, what I claim as new, and desire to secure by Letters Patent, is—

The design for cane or umbrella handles, substantially as herein described and shown. 30

In testimony of which invention I have hereunto set my hand.

HENRY O. SCHMIDT.
